UNITED STATES PATENT OFFICE.

JULIUS GLUCK, OF NEW YORK, N. Y., ASSIGNOR, BY MESNE ASSIGNMENTS, TO OHMER FARE REGISTER COMPANY, OF DAYTON, OHIO, A CORPORATION OF NEW YORK.

INITIAL-CHARGE-INCREASING MECHANISM.

Application filed February 1, 1923. Serial No. 616,367.

This invention relates to taximeters of the type used on automobiles and other public vehicles where a preliminary fee called the "initial charge" is usually registered upon the face of the meter as the minimum tariff for the service of the vehicle.

Heretofore it has been the practice to set the fare drums so as to register a fixed initial charge which would apply to all trips uniformly, and to that end it has been necessary to originally set the ten cent drum of the fare indicator at the correct position on the drum shaft to register the proper initial charge on the face of the meter. As is well known the cents indication is usually permanently placed on the dial of the meter by a fixed numeral, as for example a naught, and if the initial charge is 30 cents the ten cent wheel for indicating the tenths of dollars will be set so that "3" will appear on the face of the dial each time the meter mechanism is reset to zero, thus making a uniform initial charge of 30 cents always on the face of the meter. In the past when it was desired to change the initial charge it was necessary to open up the meter and set the ten cent wheel to show the desired numeral in combination with the cents numeral of the cents indication.

However, it is desirable in some instances to permit this initial charge to be quickly varied by the chauffeur according to the particular zone in which the cab may be operating. For instance, if the cab is operating within a certain radius in which the initial charge is 30 cents, but is called upon to go into a zone of greater radius, the initial charge must be increased to 40 cents, for example. Therefore, it is desirable to have means under the control of the operator to permit the initial charge to be changed from 30 cents to 40 cents immediately, without the necessity of opening up the meter casing and resetting the drum to show the new initial charge.

Accordingly, the present invention has primarily in view simple, practical and reliable means which is locked when the flag is in the vacant position but which is released as soon as the flag is placed in a tariff position so that in the event the initial charge is to be changed the operator of the cab can easily make the desired advance by simply turning an authorized knob or key. In that connection however, it is pointed out that the construction is such that after the initial fare has been

raised to the predetermined limit it will be impossible to thereafter raise the charge further and thus prevent fraud on the passenger by continually increasing the initial fare increment.

With the above and other objects in view which will more readily appear as the nature of the invention is better understood, the same consists in the novel construction, combination and arrangement of parts, herein-after more fully described, illustrated and claimed.

A preferred and practical embodiment of the invention is shown in the accompanying drawings, in which:

Figure 1 is a perspective view of a meter showing the initial charge registered on the face thereof.

Figure 2 is a vertical sectional view illustrating the fare drums and the means for increasing the initial charge, the parts being shown as they would appear when the flag is in the up or vacant position.

Figure 3 is a detail sectional view taken on the line 3-3 of Figure 2.

Figure 4 is a view similar to Figure 2 after the initial charge has been increased.

Figure 5 is a view similar to Figure 3 showing the position of parts after the initial fare has been registered, and while the flag is on one of the tariff positions.

Figure 6 is a detail sectional view taken on the line 6-6 of Figure 5.

Similar reference characters designate corresponding parts throughout the several figures of the drawings.

In carrying the invention into effect it is proposed to embody the same in a meter of standard construction, for example of the type shown in my co-pending application, Ser. No. 515,920 filed November 17, 1921, or any other type of taximeter where it is necessary or desirable to increase the initial charge quickly by advancing one of the fare drums one tooth of their cycle.

In Figure 2 the fare drum is designated generally as D and is provided with the usual toothed operating wheel D', the same engaging with an intermediate operating wheel E having thereon a hub portion F provided with a toothed member G. When it is desired to advance the fare drum D one notch to bring the next higher numeral into view on the face of the meter the mechanism constituting the present invention is brought into

play whereby the pivoted pawl 1 will engage the toothed member G and move it the distance of one tooth thereby to cause the wheel E to advance the drum D the space of one numeral on the face of the meter.

The said spring pressed pawl 1 is carried on a lever or actuator 2 which is pivotally supported as at 3 and maintained in its normal elevated position by a spring 4. The 10 pawl 1 is pivoted on a stud 23 and is held against a pin 24, carried by the actuator 2, by means of a spring 25. A pin 26 carried by a bar 27 mounted on the frame of the machine guides the pawl 1 into engagement with 15 the toothed member G. Projecting from one side of the lever 2 is a tooth or lug 5 adapted to be engaged by the shoulder 6 upon an actuating arm 7 which is pivotally connected as at 8 to a locking lever 9. Said locking 20 lever is pivotally supported on the meter frame at one end as at 10 and is also provided at its opposite end with a foot 11 adapted to be engaged and released by the cam 12 carried by a disk 13 on the flag shaft 14 of the 25 meter.

For the purpose of maintaining the locking lever 9 in its elevated position, in which it is placed by virtue of the flag being in the vacant position a chauffeur controlled 30 latch lever 15 is provided. This latch lever is mounted on a stud shaft 16 in the back of the meter frame and is provided with an exterior knob or finger engaging portion 17 preferably integral therewith so that when 35 the knob is engaged the latch lever 15 may be rocked providing of course the flag has been turned from its vacant position into one of the tariff positions. The latch lever 15 is provided with a pin 27 to which is secured 40 a spring 28 secured to a pin 29 carried by the framework of the machine, the spring 28 extending at approximately a right angle to the line connecting the pin 27 and shaft 16. The locking lever 9 is provided with a 45 pin 31 to which is attached a spring 30 having its other end connected with a fixed part of the frame, the object of the spring 30 being to assist gravity in pulling the lever 9 downwardly when the cam 12 has passed beyond the foot 11.

When the latch lever is in its normal position as shown in Figures 2 and 3, the locking lever 9 is supported upon the shoulder 18 of the tongue 19 on the latch lever 15, but 55 when the operator throws the flag and thereafter manipulates the knob 17 to rock the latch lever in the direction of the arrow shown in Figure 3 the locking lever 9 will be unseated from the shoulder 18 so that the 60 said tongue 19 will drop into the notch 20, the latch lever 15 being moved against the tension of the spring 28 and the locking lever 9 being moved by means of the spring 30. When the locking lever 9 drops off of the 65 shoulder and the nose 19 moves into the

notch 20 the locking lever drops downwardly and carries with it the actuating arm 7 which in turn pulls down the lever 2 carrying the pawl 1 thereby to cause the pawl to move the toothed member G the distance of one tooth. Also, as will be seen from Figure 3 the arm 7 is provided with a clearing finger 7^a adapted to engage with a lug 7^b in such a manner that when the lever 9 pulls the arm 7 downwardly the inclined edge of the clearing finger 7^a will cause the arm to shift outwardly as shown in Figure 5 and thus enable the shoulder 6 to clear the projection 5 on the lever 2, thereby permitting the lever 2 to immediately move back to its normal position under the influence of the spring 4 and clear the path of the tooth G on the wheel E as it rotates.

Also when the lever 9 moves downwardly to pull the arm 7 and thus actuates the lever 2 which in turn moves the fare drum up one notch, the counter operating extension 9^a thereof moves downwardly to actuate the lever 21 which in turn operates pawl 22 of a counter device C which registers the number of times that the initial fare has been increased from the normal initial charge to the advanced initial charge.

As previously stated, when the flag is in the vacant or for hire position it is impossible to operate the knob 17 to advance the extras drum one notch. This is due to the fact that the parts are in the position shown in Figures 2 and 3 of the drawings from which latter it will be observed that the disk 13 is provided with a lug 13^a which is disposed in obstructing relation to the free end 15^a of the lever 15 while the lever 9 is held supported on the shoulder 18 and also upon the cam 12. With the parts in the positions shown in Figure 3 it will be apparent that the knob 17 cannot be moved.

However, as soon as the flag is moved into one of the tariff positions, as indicated by the full line position in Figure 5, the lug 13^a will be moved out of the path of the end 15^a of the lever 15 and the operator can move the latch lever 15 through the medium of the knob 17. When the knob 17 is moved the part 9^b of the lock lever 9 will be unseated from shoulder 18 thus permitting the lever 9 to drop and carry with it the arm 7 which actuates the lever 2. Also when this takes place the end 11 of the lever 9 will rest upon the circular surface of the disk 13 as shown in Figure 5.

In case it was unnecessary to operate the knob 17, the locking lever 9 and latch lever 15 would remain in the position shown in Fig. 3 even when the flag shaft 14 had been rotated into the position shown in Fig. 5.

It is necessary to retain the actuating arm 7 in its depressed condition after it has once been operated, for while the toothed member G will pass beyond the pawl 1 after the arm

7 has been lowered, yet the operating wheel D' will be rotated by the taximeter so that subsequently when the toothed member G had made a complete revolution it would be 5 in such a position that it could be actuated again. By holding the arm 7 in its depressed position while releasing the actuator 2 so that it is raised by means of the spring 4, the toothed member G is permitted to rotate 10 with the operating wheel D', and the pawl 1 does not interfere with such rotation nor can the pawl 1 be again operated.

Due to the fact that the nose 19 of the lever 15 is held in the locking notch 20 of 15 the locking lever 9 it will be impossible to turn the knob 17 but once while the flag is in one of the tariff positions. Since it is impossible to operate the knob 17 more than once while the flag is in tariff position, it is obvious 20 that the actuating arm 7 can only be actuated once. The essential feature is to prevent the actuation of the arm 7 more than once after each throwing of the flag. Therefore, an absolute check on the manipulation 25 of the lever 2 more than once in the cycle of the flag is prevented. It will also be understood that the locking lever 9 remains in its original set position unless the knob 17 is turned by the operator. That is to say, if the 30 meter is set to operate on a 30 cent initial charge, each time that the mechanism is reset to zero, the initial 30 cent charge will appear on the face of the meter, and the meter will continue to operate on the 30 cent initial 35 charge basis unless and until the operator trips the knob 17.

I claim:—

1. An initial charge increasing mechanism for flag controlled taximeters including in 40 combination with a fare drum and the operating wheel therefor, of an actuator for moving said wheel through an arc sufficient to move the fare drum ahead one numeral, and manually actuated means for operating 45 said actuator including an operator's knob on the outside of the meter casing and means for locking said knob after being once manipulated until the flag of the meter has been again reset.

50 2. An initial charge increasing mechanism for taximeters controlled by a flag and including in combination with a fare drum and operating wheel therefor, of an actuator for said wheel and a member on said wheel adapted to be struck by said actuator, means for manipulating said actuator including a manually operated knob, and means for locking said knob after it has once been manipulated until the flag of the meter has been again 55 reset.

60 3. An initial charge increasing mechanism for taximeters comprising means for advancing one of the fare drums to increase the initial charge, said means including a spring tensioned lever, a pawl carried by one end

of said lever, a pivoted locking lever, means carried by said locking lever for actuating said spring tensioned lever, a pivoted lever having an exterior operating knob for controlling the operative movement of said locking lever.

4. An initial charge increasing mechanism for the fare drums of taximeters comprising means for moving one of said fare drums a predetermined distance, an operator-controlled knob having connections for actuating said means for moving one of the fare drums, a flag controlled shaft and means on said flag controlled shaft having means for locking said connections when the flag shaft 75 is in its normal position.

5. An initial charge increasing mechanism for the fare drums of taximeters comprising means for moving one of said fare drums a predetermined distance, an operator-controlled knob, a pair of spring tensioned levers one of which is actuated by the operator-controlled knob, an arm carried by the other of said levers for actuating said means for moving the fare drum, and means for returning and locking said spring tensioned levers to their normal position after they have been actuated by said knob.

6. An initial charge increasing mechanism for taximeters including an actuator for advancing one of the fare drums a predetermined distance, and means for operating said actuator, said means comprising a pair of levers, springs to hold said levers under tension, means on said levers for holding the same normally spaced apart against the tension of said springs, an operator's knob for moving one of said levers for moving the same with relation to the other lever, and a connection between one of said levers and the actuator.

7. An initial charge increasing mechanism for taximeters including an actuator for advancing one of the fare drums a predetermined distance, and means for operating said actuator, said means comprising a pair of levers having separate pivots and having projecting portions which normally engage, springs to hold said levers under tension, an arm carried by one of said levers for operating the actuator, operator-controlled means for moving one of said levers, and means for locking said levers in their normal position and resetting the same.

8. An initial charge increasing mechanism including an actuator for moving one of the fare drums, a predetermined distance, manually operated means including a plurality of levers one of which is adapted to engage the actuator for imparting a quick movement thereto, means whereby said levers become locked after imparting the quick movement to said actuator, a flag shaft, and means on said flag shaft for holding said levers locked when the flag is in vacant position, and also 120 125 130

resetting the same during the resetting movement of the flag shaft.

9. An initial charge increasing mechanism for taximeters including the combination with the fare drums, flag, and fare drum operating means, of means for advancing one of said fare drums to increase the initial charge, said means including a single tooth associated with one of the fare drum operating wheels, a spring tensioned lever normally maintained in an elevated position, a pawl carried by one end of said lever for engaging said single tooth, a pivoted locking lever, an actuating arm pivotally connected with said locking lever and adapted to actuate said spring tensioned lever carrying the pawl, a pivoted latch lever having an exterior operating knob, and means whereby the locking lever and latch lever become interlocked when the knob has been once actuated to prevent further manipulation of the lever carrying the pawl.

10. An initial charge increasing mechanism for taximeters including the combination with the fare drums, flag, and fare drum operating means, of means for advancing one of said fare drums to increase the initial charge, said means including a spring tensioned lever carrying a pawl, a wheel engaging with the fare

drum, a single tooth on said wheel adapted to be engaged by said pawl, a spring for maintaining the pawl carrying lever normally elevated, and means for actuating said pawl carrying lever including a pair of pivoted levers, an actuating arm carried by one of said levers and adapted to engage with said pawl carrying lever, means whereby said actuating arm is disengaged from the pawl carrying lever as it nears the end of its operating stroke thereby to permit the pawl carrying lever to return to normal position, and an exterior knob associated with one of said pivoted levers for operating the same.

11. An initial charge increasing mechanism for taximeters including the combination with the ten-cents fare drum and the flag, of means for advancing the ten-cents drum, said means including an exterior operating knob adapted to be engaged by the operator, means whereby said knob becomes locked after one actuation, a counter device, and means for operating said counter each time the initial charge increasing mechanism is operated.

In testimony whereof I hereunto affix my signature.

JULIUS GLUCK.
